UNITED STATES PATENT OFFICE.

HECTOR ALLIOT, OF LOS ANGELES, CALIFORNIA.

MEANS FOR CARBONATING LIQUIDS.

1,148,817.

Specification of Letters Patent.

Patented Aug. 3, 1915.

Application filed May 20, 1911. Serial No. 628,582.

To all whom it may concern:

Be it known that I, HECTOR ALLIOT, a citizen of the United States, residing at Los Angeles, in the county of Los Angeles and State of California, have invented a new and useful Means for Carbonating Liquids, of which the following is a specification.

The chief object of the present invention is to provide means by which carbon dioxid gas can be produced and applied to certain uses automatically, spontaneously, and at small cost. Its general application is to the carbonating of beverages, and to preventing and arresting fermentation and oxidation in solid and liquid foods by the chemical production and practical application of carbon dioxid gas under pressure within a vessel containing the substance to be carbonated.

Various forms of the generator may be employed in conducting the process and in each case the process consists in the retarded automatic and spontaneous production of carbon dioxid gas by the chemical reaction of an alkali and a base in compressed form and in contact with a suitable liquid, as water.

Tartaric acid and bi-carbonate of soda are the acid and base preferred for common use. These may be used in any practical form.

In carrying out this invention the acid and base may be in the form of one or more compressed bodies as pellets or tablets, in the proportion by weight of one part of the acid to three parts of the base.

In performing the operation, water to the amount of six times that of the tablet is required but an excessive quantity of water may be used.

The accompanying drawings illustrate several forms of apparatus invented by me for the purpose of carrying out this invention.

Figure 1 is a view of apparatus constructed in accordance with this invention. Fig. 2 is a view of a siphon bottle constructed in accordance with this invention. Dotted lines indicate the charging position of the carbonating receptacle shown in Fig. 1 which has been removed after charging the vessel. Fig. 3 illustrates a form of carbonator with a removable generator as applied

to fruit jars or cans. Fig. 4 is a view of the top of a soda water bottle provided with a generating stopper in accordance with this invention. Fig. 5 is a view of another form in which a generator is made in the form of a stopper.

As a first step in carrying out this invention, tablets composed of the requisite acid and alkali as tartaric acid and bi-carbonate of soda in powdered form and in proportion of 1 to 3 by weight and thoroughly mixed will be compressed by hydraulic pressure in a common tablet compressing machine to a hard solid form.

In the form shown in Fig. 1, the vessel 1 is provided with a threaded neck 2 onto which is screwed the generator body or receptacle 3 that is provided with a threaded socket 4 screwed onto the neck 2, and is provided above said socket with a floor 5 through which a tube 6 opens. Said tube extends above the level of the threaded top 7 of the generator receptacle and the screw-cap 8 is screwed onto said screw-threaded top. The capped receptacle thus constitutes a pressure tight stopper for the mouth of the vessel. The bore 9 of the tube is preferably of small diameter as it is designed only as a gas passage; and the receptacle 3, cap 8 and vessel 1 are all made of sufficient strength to retain gas under a desirable pressure with a safe co-efficient of strength for the purposes required.

To carbonate a liquid with apparatus of the character shown in Fig. 1, the vessel 1 will first be filled as desired with the liquid, as water, cider, milk, syrup, fruit juice or the like to be carbonated, and then the receptacle 3 will be screwed onto the neck 2 and the cap 8 being removed, the chamber of the body will be supplied with a charge of water exceeding about six times or more the weight of one of the tablets. Then a tablet 10 will be dropped into the charge of water and the cap 8 will be quickly screwed into place. The reaction which then takes place between the acid and alkali in contact with the water will generate carbon dioxid gas 100 which flowing through the bore 9 of the tube enters the vessel and changes the liquid contents thereof. By reason of the retarded reaction caused by the solidity of the tablet

the closure, formed by the cap can be fixed in place with a negligible loss of gas.

In the form shown in Fig. 2 the vessel 11 is provided with an internally screw-threaded neck 12 into which will be screwed the externally threaded tubular stopper 13 provided at its lower end with a valve seat 14 against which it is arranged to seat a valve 15 having a stem 16 extending up into the bore 17 of the stopper onto the top of which is screwed a perforated head 18 between which and the floor of the cavity in the stopper is interposed a spring 19 to normally close the valve 15. Said valve may be 15 screwed onto the valve stem for convenience.

The tube 6 of the removable generator projects downward from the floor 5 to depress the head 18 and opens the valve when the generator is screwed into place on the stopper 13 which in this instance forms a neck to take the place of the neck in Fig. 1.

In the form shown in Fig. 3, the cap 31 of the vessel that in this instance is a fruit jar 32, is provided with the same form of contrivance as that shown in Fig. 2, excepting that instead of threading the generator internally to screw onto a neck, the generator body is threaded externally at the bottom to screw into a socket 33 which contains the valve stem and spring and the lower end of the tube 6 depresses the valve head when screwed into place and releases the same allowing the valve to close after the generator is unscrewed at the end of the carbonating operation. The generator in this instance forms a stopper that closes communication between the interior of the vessel and the external air. After the charging has been effected with this form, the generator may be removed and applied to other vessels.

In the form shown in Fig. 4, the soda bottle 34 is of a common construction provided with a hollow glass or porcelain stopper 35 provided internally with a tube 36 and also provided with a screw cap 37. The tube 36 communicates with the bottle when the stopper is held in place by the common lever arrangement 38. Hermetical sealing is effected by the rubber gasket 39. To charge the bottle, the liquid to be carbonated will first be placed therein, then the hollow stopper will be applied and a charge of water put into the receptacle; then the compressed tablet will be put into water and the cap 37 screwed home. The gas generated then passes into the contents of the vessel. The tubes 6 and 36 desirably extend above the top of the receptacle designed to hold the 60 charge of water with the tablet, so that there will be no liability that the contents of the receptacle will reach the interior of the vessel in the filling and usual handling of the vessel while the generator is attached there-

to for the reason that the contents of the receptacle 1, 11, 32 or 34 as the case may be will preferably be pure water such as a mineral water or distilled water whereas the water used in the receptacle 3 or 35 as the case may be will be contaminated by the 70 chemicals that are used to produce the gas.

In practical use solid tablets of acid and alkali in quantities and proportions for charging different volumes of liquid will be provided. For charging the contents of a 75 quart vessel the tablets should each contain approximately one gram of acid and three grams of tartaric acid. The sediment resulting from the chemical reaction will be a very small quantity of tartrate of soda which will 80 be innocuous and can be readily washed out when the generator is removed for recharging. By thus supplying a closed vessel with substance to be carbonated and then supplying to a receptacle communicating therewith, a charge of water and a solid compressed body of a composition composed of acid and alkali in the proportion stated and then closing the receptacle, the liquid or other substance in the vessel can be effectively charged for domestic or other use without the necessity of bottling or carbonating works, thus enabling the domestic or other user to carbonate his own beverages, fruits, etc., in a convenient and inexpensive 95 way.

It is thus seen that I have provided a vessel with a detachable hollow stopper having a cap and provided with a passage opening from the bottom of the stopper at a distance 100 above the floor of such chamber and communicating with the interior of the vessel, so that the process of carbonating the beverage can be carried out in a very simple manner by simply applying the stopper to 105 the vessel, removing the cap, inserting the tablet and supplying the necessary liquid and then screwing the cap of the stopper tightly in place before the tablet has greatly dissolved and that the stopper can be readily removed when it is desired to make the 110 contents of the vessel available for use.

I claim:

1. The combination with a vessel having an orifice and adapted to contain fluid such as distilled water; of a hollow stopper detachably mounted on the vessel and comprising a receptacle for chemicals, a detachable hollow cap to close the receptacle, and a tube extending from the base of the stopper to 120 above the top of the receptacle and into the cap and detached from the cap substantially as and for the purpose set forth.

2. The combination with a vessel having an orifice and designed to contain water or 125 beverages, of a receptacle detachably mounted to close said orifice and designed to hold chemicals, a tube opening into and extend-

ing up from said orifice to above the level of the top edge of the receptacle, and a detachable hollow cap screw-threaded onto the receptacle and spaced apart and free from said tube so that the receptacle cannot be filled so as to overflow into the tube when the cap is detached.

In testimony whereof, I have hereunto set my hand at Los Angeles, California, this 8th day of May, 1911.

HECTOR ALLIOT.

In presence of—

JAMES R. TOWNSEND,
L. BELLE RICE.
